ART OF SEPARATING MIXED GASES

William L. De Baufre, Orange, N. J.

Application June 16, 1931, Serial No. 544,735

13 Claims. (Cl. 62—122)

This invention relates to improvements in the art of separating mixed gases, the invention being particularly useful in separating air and obtaining very high purity oxygen or nitrogen or both.

One of the primary objects of the invention is to simply and effectively remove impurities and more particularly lubricants carried into the system from the compressors.

Another object of the invention is to recover more highly volatile gases in a relatively pure state.

More specifically the invention has to do with the provision of a novel and improved arrangement of vaporizer portions of rectifying columns for providing the liquid refluxes in the system.

The foregoing, together with such other objects and advantages as may hereinafter appear, or are incident to the invention, are realized by the construction which I have illustrated in the preferred form in the accompanying drawings, wherein

Fig. 1 is a diagrammatic view partially in side elevation and partially in section illustrating one form of the invention, and

Fig. 2 is a similar view illustrating another form of the invention.

Referring now to the drawings the air separation plant comprises two interchangers A and B, a liquefier C, an exchanger K, a purifier M and a rectifying column made up of a pot E, a preliminary tray section F, a vaporizer section G, and a main tray section H. An expansion engine D may be provided as shown in Fig. 1 or the necessary refrigeration can be obtained by throttling as indicated in Fig. 2.

Air compressed to the necessary operating pressure enters the system at the air inlet 1. With valves 2, 5 and 7 open and valves 3, 4 and 6 closed, the compressed air passes through interchanger A and then through interchanger B, leaving the latter through pipe 8. Valves 9 and 10 should be closed and valves 12 and 13 open. Then the nitrogen from the rectifying column and the oxygen from the exchanger will be returning through interchanger B and not through interchanger A. In interchanger B, the compressed air will be cooled by the returning oxygen and nitrogen.

After leaving interchanger B, the compressed air may all pass into liquefier C as indicated in Fig. 2, or it may divide as indicated in Fig. 1, part going to expansion engine D through pipe 16. Liquefaction is produced in liquefier C by the returning oxygen from exchanger K and the returning nitrogen from the main tray section H.

The preliminary tray section F contains a num-

ber of trays arranged to cause the rising vapor to bubble through liquid flowing down from tray to tray. In Fig. 1, the expanded air from expansion engine D is introduced near the bottom of the preliminary tray section while the liquefied air from liquefier C is introduced into a tray some distance above the bottom. In Fig. 2, the partly liquefied air from liquefier C first passes through the coil in pot E before being throttled through valve 62 into one of the trays of the preliminary tray section.

Leaving the uppermost tray of the preliminary tray section, the vapor of nearly pure nitrogen passes through pipe 23 external to the column to the space above the upper tube sheet of vaporizer section G. The vapor then passes down through a larger number of small tubes 25 in the vaporizer section and is partly condensed. Selective liquefaction is avoided in the vaporizer section by having the vapor partially liquefy as it passes downward through the tubes therein. The remaining vapor leaves through pipe 26. The liquefied portion passes through liquid sealed tubes 27 and forms the reflux liquid for the preliminary tray section.

This reflux liquid interacting with the rising vapor through the trays of the preliminary tray section causes an oxygen-rich liquid to collect in pot E. This liquid is throttled through pipe 30 by means of valve 31 and enters the main tray section at 32. Flowing down from tray to tray, this liquid finally flows through pipe 33 to the space surrounding the tubes in vaporizer section G. The liquid will boil by heat transfer from the condensing vapor within the tubes and the resulting vapor will leave through pipe 34 and enter the bottom of the main tray section.

In the vaporizer section G the oxygen-rich liquid is fractionated by boiling so that the portion of this liquid leaving through pipe 36 is of higher purity than the liquid entering the vaporizer section. In exchanger K, the vaporization of the oxygen-rich liquid is completed, part of the resulting vapor returning through pipe 39 to liquefier C while the remainder returns through pipe 41 to the main tray section of the rectifier.

The constant flow of liquid from vaporizer section G into exchanger K carries with it lubricant which has passed into the system from the compressor and this lubricant will accumulate in the exchanger K. By closing valve 36 the liquid in exchanger K will partially boil away and the remaining liquid may be discharged through a drain 52 provided for that purpose, thus carrying out of the system completely all the accumu-

lated lubricant. The operation of the rectifying column will be affected but slightly by so doing and normal operation is quickly attained by re-opening valve 36. Thus the accumulation of lubricant is completely discharged from the system with very little loss of liquid oxygen.

The vapor which left vaporizer section G through pipe 26 enters exchanger K and passes upward through the tubes therein where its liquefaction is completed, with the exception of a small portion containing the more volatile gases neon, hydrogen and helium. An upward flow is used in this exchanger in order, by selective liquefaction, to obtain these more volatile gases at the top of the exchanger from which they pass through purifier M. The liquefied portion flows back into pot 43 at the lower end of exchanger K from which it is throttled through pipe 45 by valve 44. This nearly pure nitrogen passes through purifier M and thence through pipe 46 into the top of the main tray section H of the rectifier in which it serves as a reflux liquid.

The gaseous mixture from exchanger K which enters the coil within purifier M is there brought into heat exchange relation with liquid nitrogen, after being throttled through valve 44. It had previously been in heat exchange relation with liquid oxygen which vaporizes at an appreciably higher temperature under the same pressure as liquid nitrogen. The more volatile gases are, therefore, further purified of nitrogen which is liquefied and separated in pot 48, returning to pot 43 through pipe 49. The purified rare gases are recovered through pipe 50 containing valve 51. In large plants the refrigeration corresponding to the low temperature of these volatile gases may be utilized by returning them through the liquefier and interchangers.

40 The external exchanger K is mounted at substantially the same level as the vaporizer section G of the rectifier. As the level of the liquid oxygen within the exchanger K and vaporizer G will be approximately the same, the tubes therein will be equally submerged in liquid whatever this level may be. For a system to produce high purity oxygen the refluxes in the preliminary and main rectifiers should be approximately the same. This requires equal amounts of heating surface in the exchanger K and the vaporizer section G. These are, therefore, made of approximately the same number of tubes.

In general the plan of operation is in accordance with the disclosure in my copending application Serial No. 544,734, filed June 13, 1931, executed of even date.

I claim:—

1. In a system for separating mixed gases, a rectifying column having a preliminary tray section, a main tray section and a vaporizer intermediate the same, and external heat exchanger mechanism for completing the vaporization of the liquid from the main tray section and substantially completing the liquefaction of the vapors from the preliminary tray section.

2. In a system for separating mixed gases, a rectifying column having a preliminary tray section, a main tray section and a vaporizer intermediate the same for providing reflux liquid for the preliminary tray section, and external heat exchanger mechanism providing the reflux liquid for the main tray section by liquefying the vapor of the preliminary tray section not liquefied in the vaporizer.

75 3. In a system for separating mixed gases, a

rectifying column having means for collecting the liquid component, and means for vaporizing said component, said last means comprising two vaporizer compartments connected in series, one of which partially vaporizes the liquid and the other of which completes said vaporization, and means whereby the latter compartment may be shut off from the former compartment and drained of liquid. 80

4. In a system for separating mixed gases, a rectifying column having a preliminary tray section, a main tray section and a vaporizer intermediate the same, external heat exchanger mechanism for completing the vaporization of the liquid from the main tray section and substantially completing the liquefaction of the vapors from the preliminary tray section, and means for withdrawing the vaporized liquid component from the external exchanger. 85

5. In a system for separating mixed gases, a rectifying column having a preliminary tray section, a main tray section and a vaporizer intermediate the same, and external heat exchanger mechanism for completing the vaporization of the liquid from the main tray section and substantially completing the liquefaction of the vapors from the preliminary tray section, the external exchanger being at substantially the same level as the vaporizer so that the tubes of each are substantially equally submerged in liquid. 90

6. In a system for separating mixed gases, a rectifying column having a preliminary tray section, a main tray section and a vaporizer intermediate the same, and external heat exchanger mechanism for completing the vaporization of the liquid from the main tray section and substantially completing the liquefaction of the vapors from the preliminary tray section, the external exchanger being at substantially the same level as the vaporizer so that the tubes of each are substantially equally submerged in liquid and the surfaces of the exchanger and vaporizer being substantially equal. 105

7. In a system for separating mixed gases, a rectifying column having a preliminary tray section, a main tray section and a vaporizer intermediate the same comprising a plurality of vertical tubes connected to tube sheets, a connection for leading vapor from the preliminary tray section to the upper ends of said tubes, and a connection for leading liquid from the vaporizer to the preliminary tray section. 110

8. In a system for separating mixed gases, a rectifying column having a preliminary tray section, a main tray section and a vaporizer intermediate the same comprising a plurality of vertical tubes connected to tube sheets, a connection for leading vapor from the preliminary tray section to the upper ends of said tubes, said connection being external to the column, and a connection for leading liquid from the vaporizer to the preliminary tray section. 115

9. In a system for separating mixed gases, a rectifying column having a preliminary tray section, a main tray section and a vaporizer intermediate the same comprising a plurality of vertical tubes connected to tube sheets, and a connection for leading vapor from the preliminary tray section to the upper ends of said tubes, a connection for discharging non-condensed vapor from the vaporizer and a liquid seal for returning liquid from the vaporizer to the preliminary tray section. 120

10. In a system for separating mixed gases, a

- 5 a rectifying column having a preliminary tray section, a main tray section and a vaporizer intermediate the same, and external heat exchanger mechanism for completing the vaporization of the liquid from the main tray section and substantially completing the liquefaction of the vapors from the preliminary tray section, the flow in the tubes of the external exchanger being upward, and means for discharging uncondensed vapor from the top of the exchanger. 12. In a system for separating mixed gases, a rectifying column having a preliminary tray section, a main tray section and a vaporizer intermediate the same, and external heat exchanger mechanism for completing the vaporization of the liquid from the main tray section and substantially completing the liquefaction of the vapors from the preliminary tray section, and means for delivering the liquid in the external exchanger to the main tray section for use as a reflux liquid. 80
- 10 11. In a system for separating mixed gases, a rectifying column having a preliminary tray section, a main tray section and a vaporizer intermediate the same, and external heat exchanger mechanism for completing the vaporization of the liquid from the main tray section and substantially completing the liquefaction of the vapors from the preliminary tray section, the flow in the tubes of the external exchanger being upward, and means for discharging uncondensed vapor from the top of the exchanger, together with means for utilizing the liquid produced in the exchanger as a reflux liquid in the main tray section and for purifying the said uncondensed vapor. 13. In a system for separating air by liquefaction and rectification, the combination of interchangers, a liquefier, a rectifying column including an internal vaporizing section and an external vaporizing portion, means for delivering the liquid produced in the liquefier to the column, and means for leading the vapor component from the rectifier and the vaporized liquid from the external exchanger to the liquefier for return therethrough and through the interchangers. 85
